REFRIGERATING APPARATUS

Carl E. L. Lipman, Chicago, Ill., assignor to Lipman Patents Corporation, Chicago, Ill., a corporation of Delaware

Application April 8, 1933, Serial No. 665,070

5 Claims. (Cl. 62--116)

This invention relates to refrigerating apparatus, and more particularly to the smaller refrigerators of the household type.

Refrigerating cabinets are now in use in which the main or larger chamber of the cabinet serves as the food compartment, and the high side of the refrigerating apparatus comprising the compressor and condenser is located in a chamber within the cabinet above the food compartment, the refrigerating apparatus being mounted on an insulated wall which serves as a dividing partition between the food compartment and the machinery compartment above it, the wall and the entire refrigerating apparatus being removable as a unit from the upper end of the cabinet. In these constructions, a considerable amount of the cabinet space is occupied by the apparatus comprising the high side of the refrigerating system, thereby correspondingly reducing the food storage space. Furthermore, adequate cooling of the compressor and condenser enclosed in the machinery compartment requires the employment of a fan in this compartment to circulate the cooling air around the compressor and condenser.

My present invention aims to overcome the objectionable characteristics of the refrigerating apparatus above mentioned by increasing the size of the food compartment space so that it extends practically to the top of the cabinet, and affords a maximum of storage space for the size of the cabinet.

My invention also aims to dispose the refrigerating apparatus in a most compact arrangement with the compressor above the food compartment and practically above the cabinet itself, and the condenser entirely outside the cabinet but below the top thereof and in proximity to one, preferably the rear, wall of the cabinet.

My invention also contemplates the elimination of the cooling fan, which is practically indispensable for the cooling of the compressor and the condenser when located in an enclosed machinery compartment, the condenser, in accordance with my invention, being cooled by a circulation of air around the condenser between the rear wall of the cabinet and the adjacent wall of the room against which the refrigerator is set, and the motor compressor unit being cooled by circulating oil from this unit through a cooling coil disposed outside the cabinet and in proximity to the condenser.

These objects are accomplished in accordance with my invention by the provision of a single compartment open top heat insulated cabinet, the open upper end of which is closed by a removable

closure of insulating material which carries the refrigerating apparatus so that the apparatus and closure are removable from the cabinet as a unit. The arrangement of the refrigerating apparatus is such that the evaporator is suspended from and beneath the closure in the food compartment, the compressor is seated in the upper surface of the closure, while the condenser and the motor compressor unit cooling coil are located at the back of the cabinet where they are supported by suitable supporting means secured to the upper face of the closure, and projecting rearwardly over the upper end of the rear wall of the cabinet.

The construction, operation and many of the inherent advantages of my invention will be readily appreciated from that embodiment thereof, selected for illustrative purposes, which is shown on the accompanying drawing and described in the following specification.

Fig. 1 is a plan view of an apparatus embodying my invention.

Fig. 2 is a fragmentary rear elevation, partially in section, of the apparatus shown in Fig. 1.

Fig. 3 is a sectional view on the line 3--3 of Fig. 1.

Fig. 4 is a view similar to Fig. 2, showing a modified form of condenser.

Fig. 5 is a fragmentary plan view with certain parts broken away, illustrating the condenser shown in Fig. 4 and its normal relation to a wall, and

Fig. 6 is a fragmentary sectional view showing the mounting of the motor compressor unit.

Referring now to the drawing more in detail, reference character 6 indicates generally a cabinet comprising upright walls of suitable heat insulating material, a portion of the front wall 7 and rear wall 8 being shown in Fig. 3, the walls together with the bottom (not shown) forming a food storage compartment 9, occupying substantially the entire space of the cabinet, said compartment being open at its upper end and having the usual door 11 through which access to the interior of the compartment is available in the usual manner in service.

The open upper end of the compartment is closed by a closure member 12, as best shown in Fig. 2, this closure being made of heat insulating material adapted to set down into the opening and form the top of the food compartment, suitable gaskets or other sealing means 13 being employed to effect an air tight seal between the closure and the surrounding cabinet walls.

The refrigerating apparatus is carried by and

removable from the cabinet as a unit with this closure. The apparatus comprises a motor compressor unit 14 of any suitable construction, but preferably of the hermetically sealed type illustrated in my pending application, Serial No. 535,638, filed May 7, 1931, this unit being seated in a recess 15 formed in the upper face of the closure and having a depressed bottom 16 so that while the unit is heat insulated by the closure from the food compartment, it projects only a limited distance above the upper face of the closure, thereby reducing the height of the assembly to a minimum.

The condenser 16 of the apparatus, shown in Figs. 2 and 3 as a condensing coil of usual construction and in Figs. 4 and 5 as of corrugated thin wall sheet metal construction, is supported at the rear of the cabinet in a manner to be later described, and is connected with the compressor by a pipe line 17 and with the float control and receiver 18, also recessed in the upper face of the closure, by a return pipe line 19.

The evaporator 21, which may be of any preferred construction but is here illustrated as being of the fluid float controlled type, is connected with the receiver by pipe line 22, and also with the suction side of the compressor by a line 23 in which is interposed a check valve and unloader 24. The evaporator is suspended by brackets 25 from the lower face of the closure 12.

In order to adequately support the condenser 16 outside the cabinet and rigidly connect it with the closure 12 so as to enable removal of the entire refrigerating apparatus as a unit with the closure from the cabinet, I provide supporting means in the form of one or more supporting members 26, two being here shown for illustrative purposes. These members may be of channel iron or angle iron construction, each comprising a portion 27 extending over the top of the closure 12 and securely fastened thereto by bolts or otherwise, these portions projecting laterally from the closure over the upper end of the rear wall 8 of the cabinet where they are bent downwardly to form vertical legs upon and between which the condenser 16 is supported. In the form illustrated, the inner flanges 28 of the supported channels serve as the actual supporting means for the condenser coils.

To insure against the accumulation of excessive heat in the sealed motor compressor unit, I employ an oil cooling coil 29 also carried by the supporting members 27, preferably above the condenser 16, this coil being connected by pipes 31 and 32 with the interior of the motor compressor unit where provision is made for circulating the oil through the compressor and around the motor to abstract excess heat units generated thereby, the oil being then circulated through the cooling coil 29 by which these excess heat units are dissipated to atmosphere. The oil circulating apparatus, which is not here disclosed in detail, may be of any suitable construction, preferably that disclosed in my pending application above referred to. The casing of the motor compressor unit is preferably covered by a heat insulating sheath or covering 20 fitted over the casing and having the peripheral flange 30 thereof engaging the upper surface of the closure.

In Figs. 4 and 5, the oil cooling coil 29 is the same as that shown in Fig. 2. The supporting members 26 in this instance are of angle rather than channel construction, and the coil 29 is carried by angle members 33 secured to one flange 75 of the angle supporting members 26. In these

figures, however, the condenser 16, instead of being of coil construction, is composed of two closely spaced sheet metal walls 34 and 35 between which the refrigerant flows, the walls being preferably of corrugated formation to increase the area exposed to the air.

With either type of condenser, when the cabinet is located with its back to the wall 40 of a room as is customary and illustrated in Fig. 5, an air circulating flue between the room wall and 10 the rear vertical wall of the cabinet is provided through which air will circulate by convection to cool the condenser and the oil cooling coils. The corrugated shape of the condenser of Figs. 4 and 5 provides in effect a series of parallel flues which 15 facilitate air circulation. Should the cabinet be located otherwise than against a room wall, a sheet of metal or other material may be attached to the rearwardly projecting flanges of the supporting members 26 to provide a flue which will 20 insure adequate cooling air circulation.

For appearance' sake, a removable hood or cover 36 is disposed over the upper end of the cabinet to enclose and conceal from view the motor compressor unit, the supports 27 and the 25 pipe lines. The usual cold control switch 37 may be provided to regulate the cabinet temperature.

It should be apparent from the foregoing that my invention provides a refrigerating apparatus 30 in which practically the entire space of the cabinet is available for food storage purposes, and that the entire refrigerating apparatus is carried by the top of the closure compartment for the storage compartment so that the closure and apparatus are removable from the cabinet as a unit for purposes of repair and replacement, and that the cabinet and unit may be shipped separately and quickly assembled by simply setting the closure into the top of the cabinet.

The details of construction illustrated and described may obviously be varied within considerable limits without departing from the scope of this invention as defined in the following claims.

I claim:

1. The combination of a cabinet providing a food compartment having an opening at its upper end, a heat insulating closure for said opening, a refrigerating apparatus attached to and removable from the cabinet as a unit with said closure, said apparatus comprising a compressor located in a recess in the upper face of the closure, an evaporator suspended in the food compartment beneath the closure and a condenser 55 at the rear of the cabinet, and supports carried by and extending rearwardly from said closure and supporting said condenser in proximity to the outer face of the rear wall of said cabinet.

2. The combination of a cabinet providing a food compartment having an opening at its upper end, a closure for said opening, supporting means secured to said closure and projecting over the upper end of one of the walls of said cabinet, a condenser carried by said supporting means 65 outside of but in proximity to said cabinet wall, an evaporator suspended in said food compartment from the lower face of said closure, and a compressor supported above the food compartment by and partially embedded in said closure, 70 said closure and the condenser, evaporator, compressor and condenser supporting means all carried by the closure being removable as a unit with said closure from said cabinet.

3. The combination of a cabinet providing a 75

food compartment open at its upper end, a removable closure for said compartment, said closure being formed of heat insulating material and provided in its upper surface with a recess, a 5 motor and compressor located in said recess, an evaporator suspended beneath said closure in said food compartment, supporting means projecting from said closure over the upper end of one of said cabinet walls, a condenser supported in 10 proximity to the outer face of said wall by said supporting means, and a removable cover disposed over said cabinet.

4. The combination with a cabinet providing a food compartment open at its upper end, a 15 removable closure for said opening, a plurality of supports secured to said closure and extending downwardly in spaced apart relation in proximity to one wall of said cabinet to form in conjunction with said cabinet wall and a room

wall against which the cabinet is set an air circulating flue, and a refrigerating apparatus carried by said closure and removable as a unit therewith from the cabinet, said apparatus including a condenser disposed within said flue formed by said supports between said cabinet. 5

5. The combination with a cabinet having a removable top, of a refrigerating apparatus removably associated with said cabinet, said apparatus including a condenser, and means extending longitudinally of the cabinet in spaced relation for supporting said condenser outside of and adjacent to the rear wall of said cabinet, said wall and the condenser supporting means in conjunction with a room wall against which the cabinet is set providing an air circulating flue 10 around the condenser. 15

CARL E. L. LIPMAN.
